Ill., assignors to Cribben and Sexton Company,
Chicago, Ill., a corporation of Illinois

Application November 18, 1944, Serial No. 564,032

3 Claims. (Cl. 126—39)

1

This invention relates to a stove, and more particularly to a stove having an oven or cooking compartment with improved closure structure.

In the use of gas ranges and other cooking stoves, it is quite undesirable that the oven door become heated during the use of the oven. Not only does this represent a waste of fuel, but the hot oven door is a hazard and inconvenience to the housewife who operates the stove.

Heretofore, attempts have been made to overcome this objection by filling the oven door with insulating materials. However, such constructions have not succeeded in preventing the access of heat to the front of the stove. In all such prior constructions, it has been necessary to have metal edges about the door which have the effect of conducting heat from the interior of the oven to the front of the door.

An object of the present invention is to provide a stove having an improved oven or cooking compartment closure, which closure is efficient in preventing the heating of the front of the oven door.

More specifically, it is an object of the invention to provide a closure for the oven opening, which closure is spaced from the door by an insulating air space. Another object is to provide such a door and closure structure which has a vertical air passage therethrough through which air may pass by convection and carry the heat from the oven, keeping the heat away from the oven door. Still another object is to provide a stove having the improved door and closure structure which includes an inner plug member spaced from the door and wherein the plug member is secured to the door by bolts inward of the periphery of the plug, which bolts may be adjusted to enable an exact fit with the opening in the oven. Other objects and advantages will be apparent as the specification proceeds.

The invention is illustrated in a preferred embodiment by the accompanying drawing, in which—

Fig. 1 is a perspective view of a stove constructed according to the invention; Fig. 2 is an enlarged sectional view in elevation, the section being taken as indicated at line 2—2 in Fig. 1; Fig. 3 is an enlarged fragmentary view showing the top of the oven door and the plug member; and Fig. 4 is a detail sectional view taken as indicated at line 4—4 of Fig. 3.

As indicated at Fig. 1 of the drawing, the improved stove has a front appearance similar to stoves already known to the art. Although the invention is illustrated by its application to

a gas range, it may be applied to any type of heater unit, including electric stoves or ranges and oil-burning stoves or ranges. The stove here illustrated has a burner section 10, an oven section 11, and a broiler section 12. The front surfaces of each section are substantially flush, and a neat appearance is presented. The accessories, such as the backboard 13, burner covers 17, knobs 14, and door handles 15 and 16, are features which may be varied as desired.

Referring now more particularly to Fig. 2 of the drawing, there is contained in the burner section 10 the burners 18 which are disposed under the openings 19 in the top plate 20. At the front, the top plate 20 joins with the vertical front panel 21.

The oven section 11, below the burner section, contains the oven compartment 22. This compartment is formed by the top wall 23, the rear wall 24, bottom wall 25, and the side walls. The top wall 23 contains an inner metallic wall 26 and an outer metallic wall 27 between which is the insulating material 28. The rear wall 24 and the side walls are similarly formed. At the front of this oven structure is the opening 29, the edges of which, at 30 and 31, are beveled, the beveled surface being inclined inwardly and rearwardly.

Closing the oven opening 29 is the plug member 32. This member has the front metallic wall 33 and the rear metallic wall 34, and between these walls is insulating material 35. At the peripheral edges of the member, the inner or rearward metallic wall is turned outwardly and secured to a flange of the outer wall by a screw 36, as more clearly shown in Fig. 3 of the drawing. It may be noted that the edge of this member is provided with a tapered surface 37. This tapered surface corresponds with the beveled surface at the edge of the oven opening 29. The plug member 32 is of such size and shape as to fit closely into the opening and to effectively close the opening.

Directly in front of the oven compartment 22 and spaced from this compartment is the oven door 40. This door is constructed with an inner or rearward metallic wall 41 and an outer or forward metallic wall 42, with insulating material 43 between these walls. At its bottom edge, it is pivotally mounted in any suitable way to the sides of the stove. In the illustrated model, interior or concealed hinges are employed and therefore do not show in a view such as Fig. 1.

The plug member 32 is secured with the door 40 by means of a number of bolts 44. This

mounting is more clearly shown in Fig. 3 of the drawing. The metallic wall 41 of the door contains the holes 45 and corresponding and opposite holes 46 are contained in the metallic wall 33 of the plug member. A bolt 44 extends through the holes 45 and 46. The head 47 of the bolt and lock washer 48 are preferably at the rear of the metallic wall 33 on the interior of the plug member. A nut 49 on the interior of the door engages the bolt and locks it tight with respect to the door. Nuts 50 and 51 are disposed on the bolt and engage the adjacent walls of the door 40 and plug member 32. These nuts provide for adjustment of the spacing apart of the door and the plug member.

It may be noted that the opening 45 in the door wall is substantially larger than the cross sectional area of the bolt 44. This feature is more clearly brought out in Fig. 4 of the drawing. The purpose of this is to permit shifting of the plug member with respect to the door either vertically or laterally to adjust the plug member for exact fit with the opening of the oven. The bolt and nut structure also allows the plug member to be secured at greater or lesser spacing from the door. This permits adjustment to make the plug come into fitted engagement when the door reaches its vertical closed position. The adjustment of the door with respect to the plug is preferably made at the factory since access to the interior of the door is needed for the tightening of the nut 49.

In the broiler section 12 of the stove, there is a second cooking compartment 55. The top of this compartment is formed by the plate 54 which has a downward extension 56 at the front. The downward extension 56 is turned inwardly at its lower edge to form the beveled edge 57. The bottom of the broiler compartment is formed by the plate 58 which forms a similar bevel at its forward edge 59.

Closing the front opening 60 in the broiler section is the plug member 65 which has the inner and outer metallic walls 66 and 67 respectively with the insulating material 68 between these walls. Its edges are tapered at 69 to correspond with the bevel of the broiler opening and it is constructed of such size and shape as to exactly fit this opening.

A broiler structure 70, within the broiler section, is carried on the rollers 71 and is adapted to move forwardly out the front opening 60 to a point where there can be easy access thereto from the front of the stove.

The broiler door 75, disposed in front of the opening 60, is constructed with outer and inner metallic walls with insulating material therebetween, a construction similar to that used in connection with the oven door 40. This broiler door 75 is pivotally mounted by concealed hinges to the sides of the broiler structure 70, the hinges being at each side near the lower portion of the door.

The plug member 65 is secured to the door 75 and in spaced relation with this door by the bolts 76, such bolt means being similar to the bolt mounting used in connection with the oven door 40. The member 65 therefore moves with the door 75 when this door is moved about its pivot. The door may be pulled forward to remove the plug member 65 from the opening 60 and to bring the structure 70 out through the broiler front opening.

The bolts 44 which secure the plug member 32 to the oven door 40 are preferably disposed in-

wardly of the periphery of the plug member. This structure avoids any substantial heat conduction to the door through the bolts. The inner metallic wall 34 is unavoidably in contact with oven heat and there is conduction through this metallic wall to the edges of the plug member. Such path of direct heat conduction is avoided by having the bolts placed inwardly of the periphery. The same may be observed with respect to the placement of the bolts 76 securing the plug member 65 to the broiler door 75.

By having the plug member 32 mounted in spaced relation to the oven door 40, there is provided an air space or passageway 80 through which the air may pass upwardly between the plug member and the door. The upper end of the passageway 80 may communicate with a duct 83 which extends horizontally across the top of the oven and communicates with the oven flue 82. In this way, the air which travels through the passageway 80 passes through the duct 83 and into the flue 82.

Where, as in the embodiment described, there is a similar construction in connection with a broiler below the oven, the air passageway extends from the bottom of the broiler door upwardly inside both broiler and oven doors into the burner section of the stove. Instead of having the oven above and the broiler below, the broiler may be disposed above the oven while still employing the improvements of this invention. The invention is also applicable to a unit in which either the broiler or oven is eliminated. If the broiler is eliminated, a conventional utility drawer or dummy panel may be substituted for it. In any event, an air inlet is provided at the lower end of the passageway 80.

The provision of the air space between the plug member and the door is effective in keeping the door at a low temperature though the oven or broiler cooking compartments be very hot. This is explained by the fact that the plug member has a minimum of heat-conducting metallic connection with the door and also by the fact that air currents may pass upwardly between the door and the plug member to carry off the heat which may be radiated by the plug member.

Although but a single embodiment of the invention is illustrated, it is evident that many widely-differing modifications may be constructed, all within the spirit and scope of the invention.

We claim:

1. In a stove, a casing providing a plurality of vertically-spaced cooking compartments, a top burner section above said cooking compartments and spaced from the compartment below by a passage leading to the rear of the stove, insulated doors carried by said stove and closing the front ends of said compartments, said doors being provided with aligned cooling passages extending vertically therethrough and communicating with the passage below said burner section, and a flue outlet means from at least one of said cooking compartments and rising vertically at the rear of the stove, said flue communicating with said passage below said burner section.

2. In a stove, a casing providing a plurality of vertically-spaced compartments and a burner section above the upper compartment, said burner section being spaced from the compartment below to provide a substantially horizontal passage over the top of the upper compartment, means for heating said upper compartment, an outlet means from said upper compartment and

rising vertically to discharge heated gases from the top portion of the stove, said outlet communicating with said passage, and doors closing said compartments, the door for said upper compartment at least being provided with a vertical cooling passage communicating with the passage above said upper compartment.

3. In a stove, a casing providing a plurality of vertically-spaced compartments and a burner section above the upper compartment, said burner section being spaced from the compartment below to provide a passage extending over and to the rear of said upper compartment, vent means for said passage leading upwardly therefrom, means for heating one of said compartments, an outlet means leading from said heating compartment to said vent means to heat the gases therein and induce suction in said passage over said upper compartment, and doors closing said compartments, the door for the upper compartment, at least, being provided with a vertical cooling passage communicating with the passage above said upper compartment.
